Another and the second option will be to move the data to another space and to store it in a distributed system. This is a good option and it is the most common approach in today's distributed system. There are different distributed systems for data storage which are being developed and used in different applications. The third option is to use a hybrid approach which is a combination of the first two approaches. This will be a good option for a system which needs to store large amounts of data and also needs to process it in real-time.

ne s'apre con un'esplosione violenta. L'esplosione è così violenta a volte da rompere tutta la struttura, che spesso non si sente funzionalmente nulla di più oltre che la folla di esplosioni nel perimetro della fabbrica.

Application October 1, 1934, Serial No. 746,407

3 Claims. (Cl. 245—10)

This invention appertains to wire cloths or wire fabrics of the type commonly used in making paper on Fourdrinier machines, and more particularly to a novel seam or means for joining the ends of the fabric together to form the desired endless construction.

The formation of this seam in the endless paper machine wires presents many difficulties, and I am aware of the fact that numerous attempts have been made to solve the problems at hand, and that many patents have been granted on seams for the Fourdrinier wires.

15 It is essential that the seams be mechanically strong, and at the same time not decrease the drainage through the cloth at this point. Also, the seam must not possess bulk, or have any projections beyond the faces of the cloth. Otherwise a line or mark will be made on the paper.

Originally it was proposed to unite the ends of the cloth by a lacing wire, and while this provided a strong joint, the same was bulky and did not possess the desired drainage. Also, the making of the seam was a tedious and lengthy operation. Later it was proposed to solder or weld the wire ends. This method possessed certain advantages, but in all of the patented constructions with which we are familiar, the soldered or welded seams are open to some or all of the objections outlined above. In most, the joints are weak and will break if the screen is bent; in others the proper drainage is not provided; and in still others the paper will be marked.

It is therefore the primary object of my invention to provide novel means for joining the ends of the warp wires of a cloth and solder the same together in such a manner that not only will a strong and durable joint be had, but one which will not mark the paper and will give the desired drainage.

40 Another salient object of my invention is to provide a screen in which the end weft or shot wires are removed and the projecting ends of the warp wires are arranged side by side in predetermined relation, and thereafter soldered or
45 brazed together, the space between the adjacent warp and weft wires of the seam being at least equal to the spaces between the warp and weft wires in the body of the screen.

With these and other objects in view, the invention consists in the novel construction, arrangement, and formation of parts, as will be hereinafter more specifically desired, claimed, and illustrated in the accompanying drawing, in which drawing:—

56 Figure 1 is a fragmentary top plan view, on

an enlarged scale, of the one end of a length of wire fabric with the end shot or weft wire removed.

Figure 2 is a similar view showing the seam, the end weft or shot wires being removed, and the warp wires being disposed in overlapping side by side relation and soldered together. 5

Figure 3 is a fragmentary longitudinal section through the adjacent ends of an endless wire cloth, illustrating the novel seam, the view being taken substantially on the line 3—3 of Figure 2, looking in the direction of the arrows.

Referring to the drawing in detail, wherein similar reference characters designate corresponding parts throughout the several views, the numerals 5 and 6 indicate the adjacent ends of a wire cloth prior to being connected. In accordance with my invention, I remove the end weft or shot wire thread of the wire screen end 5, and the end weft or shot wire of the screen end 6. This leaves the projecting ends 9 and 10 on the warp wires 11 and 12 of the screen ends 5 and 6. As clearly shown in Figure 2 of the drawing, the projecting ends 9 and 10 of the warp wires 11 and 12 are arranged in overlapping side by side relation, and by closely examining this figure it will be noted that like warp wires of the end sections 5 and 6 are arranged in close relation. This is done so that the curvature of the adjacent wire ends will be the same, and I prefer to roll these ends to slightly flatten the same to assure their proper relation.

After the ends of the warp wires are arranged as shown and described, the same are united by soldering, brazing, welding, or fusing. It is preferred to solder the ends together, and a novel method (which forms the subject matter of a separate application) is practised to effect the desired soldering operation. It is sufficient to note, in the present case, that after the warp wire ends 9 and 10 are placed in their side by side relation, liquid silver solder is applied thereto by means of a fine camel's hair brush. Heat is then applied, preferably by means of a torch (1350°). This gives a line of solder 13 between and over the warp wire ends 9 and 10. Due to the rolling or straightening out of the warp ends 9 and 10 the solder 13 does not project beyond the opposite faces of the screen. By arranging the ends of the warp wires in side by side relation, a strong and durable joint is had, in that the wires brace one another and cannot be readily pulled apart.

Obviously, the spaces formed in the seam are substantially equal to the spaces in the body of 55

the wire fabric. Hence, drainage at the seam is assured. Likewise, the seam is not a bulky one, in that the warp wires are disposed side by side instead of in longitudinal alignment, as heretofore proposed.

Changes in details may be made without departing from the spirit or scope of my invention, but what I claim as new is:—

1. The method of producing a seam in a wire fabric, which comprises removing the end weft wire of each of the fabric parts to be joined, placing the projecting ends of the warp wires in side-by-side relation, and joining the sides of the overlapping ends of the warp wires by solder.
- 10 2. The method of producing a seam in a wire fabric which comprises removing the end weft

wires of each of the fabric parts to be joined, arranging the projecting ends of the warp wires side-by-side in overlapping relation with the warp wires out of longitudinal alignment, and soldering the sides of the overlapping ends of the warp wires together, the solder being spaced equidistantly from the adjacent weft wires of the fabric parts.

- 15 3. A wire fabric comprising fabric parts, each having warp and weft wires, with the end weft wires removed and having the warp ends disposed side-by-side in overlapped relation and out of longitudinal alignment, and means connecting the sides of the overlapping ends together.

15 OTTO A. ABENDROTH.
